CARRYING CASE FOR MICROSCOPES

Kenneth D. Maier, Mendon, N.Y., assignor to Bausch & Lomb Incorporated, Rochester, N.Y., a corporation of New York

Filed Mar. 23, 1967, Ser. No. 6,360

Term of patent 14 years

(Cl. D87—5)

The dominant features of my design are shown in full lines in the drawings.

I claim:

The ornamental design for a carrying case for microscopes, substantially as shown and described.
